UNITED STATES PATENT OFFICE.

THOMAS C. MCCOLLUM AND JAMES H. HUGHENS, OF BIRMINGHAM, ALABAMA.

ELECTRIC HEADLIGHT LAMP.

Application filed July 28, 1925. Serial No. 46,640.

This invention relates to an improved electric lamp especially designed for use in connection with automobile headlights and seeks, among other objects, to provide a lamp wherein the intensity of the light will be increased while, at the same time, headlight glare will be eliminated.

5

The invention seeks, as a further object, to provide a lamp embodying a mirror arranged to screen the lamp filament from direct observation and disposed to reflect the light rays downwardly toward the bottom of the headlight reflector whence the rays will be projected forwardly in a substantially horizontal beam.

10

And the invention seeks, as a still further object, to provide a lamp which may be readily manufactured and which may be used in connection with ordinary existing headlights.

15

Other objects of the invention not above specifically mentioned will appear as the description proceeds.

In the accompanying drawings:

20

Figure 1 is a sectional view showing our improved lamp installed in a conventional motor vehicle headlight.

Figure 2 is a detail side elevation of the lamp, partly broken away and shown in section to illustrate the mounting of the mirror.

25

Figure 3 is a transverse sectional view on the line 3—3 of Figure 2, looking in the direction indicated by the arrows.

In accordance with the present invention, the lamp is formed with a base 10 of approved construction and connected at its smaller end with the base in the usual manner is a substantially unguaranteed bulb 11, preferably of clear glass. In other words, the bulb is of frusto conical shape, but the base thereof is oblique to the axis of the bulb. Appropriately mounted within the bulb is an axially disposed filament 12 electrically connected with the base, and closing the bulb at its larger end is a preferably flat mirror 13 disposed obliquely to the axis of the bulb. As shown, the top of the mirror is tilted toward the base 10 and the mirror is preferably formed of a separate flat glass disc provided at its inner side with a

silver coating 14. As brought out in Figure 2, said disc fits within the larger end of the bulb and is preferably fused at its periphery therewith, although said disc may be otherwise hermetically connected with the bulb. Thus, the mirror may be separately formed and later assembled with the bulb, and since the silver coating 14 is disposed at the inner side of the mirror disc, said coating is housed and protected by the bulb.

In Figure 1 of the drawings, we have illustrated the lamp in position in a conventional motor vehicle headlight. The shell of said headlight is indicated at 15, and mounted within the shell is a parabolic reflector 16 carrying a socket 17, while a front lens 18 closes the reflector at its larger end. As will be observed, the base 10 of the lamp is engaged in the socket 17 and the lamp is so disposed that the mirror 13 is tilted vertically and rearwardly with respect to the reflector 16. Accordingly, light rays emanating from the filament 12 and striking the mirror will, as suggested in dotted lines, be reflected downwardly by the mirror against the lower portion of the reflector, when said rays will be again reflected forwardly in a substantially horizontal beam. By disposing the mirror at the proper angle with respect to the filament, the greater portion of the light rays may be thus reflected downwardly and forwardly so that the light will be concentrated in a beam of intense brilliancy. At the same time, the mirror will shield the filament from direct view and thus eliminate the glare which would otherwise be experienced.

Having thus described the invention, what we claim is:

1. The combination with a motor vehicle headlight having a reflector, of a lamp mounted axially of the reflector and including an unguaranteed bulb, a filament disposed axially of the bulb, and a mirror closing the larger end of the bulb in front of the filament and inclined with respect to the axis of the bulb for reflecting light rays emanating from the filament downwardly against the lower portion of said reflector.
2. In an electric lamp, the combination of a base, a frusto conical bulb connected at

its smaller end with the base, the base of reflecting downwardly the light rays emanating from the filament.
the bulb being inclined with respect to the axis of the bulb, a filament supported axially of the bulb, and a flat disc closing the larger end of the bulb and silvered at its inner side to form a mirror disposed in inclined position in front of the filament for

In testimony whereof we affix our signatures.

THOMAS C. McCOLLUM. [L. S.].
JAMES H. HUGHENS. [L. S.]
